UNITED STATES PATENT OFFICE.

GEORGE H. KIRSCH, OF LARKSPUR, CALIFORNIA.

PULP-FORMING MACHINE.

Application filed November 20, 1924. Serial No. 751,010.

This invention relates to a machine whereby articles, such as paper cups, bottles, pie plates, berry baskets, and the like may be formed from wood pulp or analogous material.

The object of the present invention is to generally improve and simplify the construction and operation of machines of the character described; to provide a machine in which two sets of molds are employed, one set to receive the pulp, temporarily shape it, and then transfer the pulp article, and the other set of molds to receive the temporarily shaped article and then permanently shape the article, dry it, and discharge the completed article; to provide means for reinforcing the pulp article while shaping it; to provide means for removing excess water by pressure, blowing and suction action before drying, and, in general, to provide a machine which is capable of quantity production, and which is automatic in operation throughout.

One form which my invention may assume is exemplified in the following description and illustrated in the accompanying drawings, in which—

Fig. 1 is a side elevation of the pulp forming machine, said side elevation being partially in section.

Fig. 2 is an end view of the machine partially in section.

Fig. 3 is an enlarged detail view of the pulp receiving molds and the actuating mechanism.

Fig. 4 is an enlarged detail view showing the mechanism whereby intermittent motion is transmitted to rotate the mold-carrying drum.

Fig. 5 is an enlarged detail view showing the valve mechanism which controls the suction and air blast on the molds carried by the drum.

Fig. 6 is an enlarged detail view showing the valve mechanism and the cam shaft actuating the same, said valve mechanism serving the function of controlling an alternate blast suction on the molds.

Fig. 7 is an enlarged detail view of the same valve mechanism shown in Fig. 7, Fig. 7 being a view taken at right angles to Fig. 5.

Fig. 8 is a perspective view of the type of mold carried by the drum.

Fig. 9 is a perspective view of the pulp receiving mold.

Fig. 10 is a perspective view of the type of mold applied to the drum when berry baskets are to be formed.

Fig. 11 is a perspective view of the mold cooperating with that type of mold shown in Fig. 10.

Fig. 12 shows the completed pulp article, to-wit, a pie plate, which is formed by the type of mold shown in Figs. 8 and 9.

Fig. 13 is a perspective view of the pulp article, to-wit, a berry box, which is formed by the type of mold shown in Figs. 10 and 11.

Fig. 14 is an enlarged cross-section showing the type of mold shown in Figs. 8 and 9.

Fig. 15 is another detail cross-section of the type of mold shown in Figs. 8, 9, and 14, Fig. 15 being shown for the purpose of describing how the pulp articles are reinforced.

Referring to the drawings in detail, and particularly to Figs. 1 and 2, A indicates a main frame in which is journaled a tubular shaft B. Carried by the shaft is a drum C, and carried by the drum in turn are a plurality of bracket arms D, on the opposite sides of which are secured pulp drying molds generally indicated at E. Disposed below the drum is a pulp receiving tank F to which pulp is continuously delivered from any suitable source, and disposed in the bottom of said tank is a fluid actuated motor G, whereby a pair of molds H is actuated.

Two sets of molds are employed, to-wit, the pair indicated at H, and the molds arranged in pairs on the drum C. For convenience of description, the molds indicated at H will hereinafter be referred to as the primary or receiving molds, and the second set of molds will be referred to as the secondary or drying molds.

Before rendering a detail description of the several parts of the machine, a brief description of the general operation will be submitted. An intermittent rotary motion is transmitted to the drum C, and the molds E, which are arranged in pairs, are therefore successively brought into alignment with the fluid actuated motor G and the primary molds H actuated thereby. An oscillating movement is intermittently transmitted to the primary molds H and during this oscillating movement they are first submerged in the pulp contained in the tank F. A suction is applied to the molds when so

submerged and their interior surfaces thus become coated with a layer of pulp. The primary molds are then oscillated and elevated to assume the full line position shown in Fig. 1, and they are thus brought to a position where they will cooperate with the molds E carried by the drum. During this operation the pulp is first subjected to pressure, suction and blowing action to remove the excess water. The primary molds are next subjected to an air blast and the molds E to a suction action, and the pulp is thus transferred from the primary molds H to the secondary molds E. After the transfer of the pulp has taken place, molds H are again lowered or submerged to receive a new coating of pulp and the drum is advanced one step to bring a new set of drying molds into position. The molds E, which have received the pulp, are now subjected to a suction action until they reach the point generally indicated at I.

The drum as a whole is enclosed by a casing or housing K and a hot or warm current of air is continuously circulated through the casing. The suction to which the drying molds E are subjected causes the warm air to pass through the pulp and the molds, and the pulp is thus dried on the molds E and the completed pulp articles are finally discharged by means of an air blast when the point I is reached. They are here removed by means of the air blast and discharged onto an endless conveyor belt L, which carries the completed pulp articles to any point desired.

A detail description of the primary molds and the mechanism actuating the same will now be rendered, and particular reference will be made to Figs. 3, 6, 8, 9 and 14. The fluid actuated motor generally indicated at G consists of a casing or cylinder housing 2. Mounted in the upper end thereof and interspaced, as shown in Fig. 3, is a pair of tubular shafts 3 and 4, and journaled on each shaft are a vane 5 and an upwardly projecting hollow arm 6. The hollow arms are in constant communication with the tubular shafts 3 and 4 through means of ports such as indicated at 7 and 8, and means are employed for intermittently applying either a suction or an air blast. Means are also employed for intermittently oscillating the vanes 5 and the arms 6, and this is accomplished by either applying a suction to the casing or cylinder G, or admitting air or liquid under pressure.

The arms 6 carry molds of the type shown in Figs. 9 and 14. These molds are intended for the purpose of forming pie plates of the type shown in Fig. 12. The molds carried by the arms 6 are identical in shape and construction and the description of one should therefore suffice.

65 The type of mold plate shown in Fig. 9

is nothing more or less than a recessed plate 9 in which are formed a plurality of perforations 10 and grooves 9a. The upper end of the arm 6 is depressed to receive the plate 9 and an interior chamber 11 is thus formed between the upper end of the arm and the mold plate 9, this chamber being in communication with the hollow arm 6, whereby the mold is supported, it being understood that the mold plates are secured to the arm 6 by bolts or other suitable means. The inner surface of the mold plate 9 is covered with one or more layers of perforated plates and screens, such as shown at 12 and 13, and an ideal supporting surface is thus formed for the reception of pulp. The particular shape of the mold plate 9 depends entirely upon the article to be formed. It appears more or less like a shallow perforated dish when pie-plates, such as shown in Fig. 12, are to be formed, but its appearance is considerably altered when berry baskets are to be formed as shown in Fig. 13; that is, the depression in the plate would in that instance be rectangular and fairly deep (see Fig. 11). It would nevertheless be perforated, as shown at 10, and it would also be covered with perforated plates and screens. In other words the construction would remain the same, but the shape would merely be altered to suit the article. The arms 6 carrying the mold plates 9, which have heretofore been referred to as the primary molds, are oscillated alternately to an elevated or lowered position, where they will be submerged in the pulp in the tank F, when it is desired to coat the inner surface of the mold plate with pulp. A suction is applied when the primary molds or plates 9 are submerged and this suction causes the water to pass through the screen covered mold plates and at the same time catches or retains the pulp, thereby forming a coating of a suitable thickness.

When the coating has been applied, the arms 6 are again oscillated and they are raised to the full line position shown in Figs. 1 and 3. The pulp is here subjected to pressure, suction and blowing action to remove the excess water and moisture, and it is then transferred to the secondary molds E by means of an air blast and suction.

The mechanism controlling the oscillating movement of the arms 6 and the primary molds carried thereby will now be described. By referring to Fig. 6 it will be noted that four valves are employed, such as indicated at 15, 16, 17 and 18. These valves are normally retained in a closed position by overhead springs, as shown, and they are raised upwardly and away from their seats by means of a cam shaft 19, which is continuously rotated in any suitable manner; that is, each valve is provided with a depending stem and these stems are engaged by the

cams indicated at 20, 21, 22 and 23. The valves shown at 15 and 16 control the movement of the vanes or pistons shown at 5, and the valves shown at 17 and 18 control the flow of fluid through the primary molds, the hollow arms 6 and the tubular shafts 3 and 4. During rotation of the cam shaft 19, cam 20 first engages the stem of valve 15 and thereby opens the same. The lower portion of the valve chamber is provided with a port 24, which is in constant communication with a suction pump (not here shown). Hence, when valve 15 is opened, a suction is created through a passage 25, which is in constant communication with a pair of central ports 26 formed in one end of the cylinder or casing G (see Fig. 3). The suction produced pulls the vanes or pistons 5 inwardly to a central position and an oscillating movement is thus transmitted to the hollow arms 6 and the primary molds carried thereby, which causes them to assume a submerged position in the pulp tank, uniform movement of the pistons 5 and the arms 6 being obtained by dividing the cylinder into two compartments by means of a central cross plate 26^a. At the moment of submersion, cam 23 engages the stem of valve 18 and raises the same. The lower portion of the valve casing is also in constant communication with a suction pump through a port 27. The upper portion of the valve casing is connected with a pipe 28, which in turn is connected with the ends 35 of the shafts 3 and 4. A suction is thus produced in the tubular shafts 3 and 4 and the hollow arms 6, and water will thus be drawn through the hollow arms and the shaft and will be delivered to the suction pump through port 27, this flow of water causing the pulp to adhere to the screen surfaces of the primary molds and thus coating them with a layer of pulp of suitable thickness. The moment a desired thickness or coating has been obtained, valve 15 closes and cam 21 engages the stem of valve 16, thus opening the same.

The upper portion of the valve housing is connected with a source of water or fluid under pressure through a port 29. This fluid under pressure passes through the open valve 16 and enters the passage 25. It flows through this passage into the ports 26 and thus enters the cylinder centrally between the vanes or pistons 5. This pressure forces the vanes outwardly to the position shown in Fig. 3, and the hollow arms, together with the primary molds carried thereby, are thus raised to an elevated position, where they will enclose the molds E, which have been previously brought to proper position by intermittent movement of the drum. Valve 18 continues to remain open during the upward movement of the primary molds and the major portion of the water is thus removed from the pulp. A squeezing or pressure action takes place the moment the primary molds enclose or contact with the secondary molds E and an air blast is also passed through the pulp 70 and excess water or moisture is thus rapidly removed. In other words the pulp is subjected to a squeezing action, an air blast and a suction. The moment the squeezing action has taken place and the excess water 75 has been removed, cam 23 moves out of engagement with the stem of valve 18 and the valve closes. Cam 22 at this time moves into engagement with the stem of valve 17. This valve is opened and an air blast is 80 admitted to pipe 27. This pipe, as previously stated, connects with the tubular shafts 3 and 4 and the primary molds are thus subjected to an air blast. The upper portion of the valve casing 17 is connected 85 with a compressor or the like (not here shown) through means of a pipe 31 and it is due to this reason that an air blast is obtained when valve 17 is opened; that is, the air under pressure enters through pipe 90 31, passes by the open valve and discharges through port 32 in the lower part of the valve casing. This port is connected with the pipe 29 and this pipe delivers the air to the tubular shafts 3 and 4, the hollow 95 arms 6, and the primary molds carried thereby. This air blast is merely momentary and it is just sufficient to free the pulp from the primary molds and to transfer the pulp to the secondary molds E. These 100 molds are at the same time subjected to a suction action and the pulp will thus adhere and will remain on these molds until dried and discharged. The primary molds are again lowered to submerged position 105 and are again coated with pulp. They are then raised and the cycle of operation is repeated and repeated as each set of secondary molds moves into position.

Several actions take place when the primary and secondary molds are brought into register. These actions are more or less simultaneous; that is, excess water and moisture are removed from the pulp, and the outer edges of the pulp article are reinforced or thickened. This can best be seen by referring to Fig. 15. The upper edge of the primary mold plate is extended vertically, as shown at 9^a, and the pulp therefore accumulates along the extended 115 surface, as shown at 9^c. When the primary mold is forced into engagement with the secondary mold E, the outer peripheral edge of the mold E, indicated at 35, serves the function of a scraper and forces the 120 accumulated pulp shown at 9^c into a compact mass, such as shown at 9^d. (See Fig. 14.) This mass in reality forms a reinforced flange or edge and to this extent reinforces and strengthens the pulp article and it, 125 130

therefore, is one of the important features of the present invention. The reinforcing action takes place at the same time that the excess water is removed and the pulp is then transferred to the secondary molds.

A detail description of the mechanism for imparting an intermittent rotary movement to the drum will next be described, and particular reference will be made to

10 Fig. 4. Formed on one edge of the drum and on its outer periphery is an annular flange 37. Formed in said flange are a plurality of interspaced notches or recesses 38. Journalled on the tubular shaft B is an arm 40. The lower end of this arm projects beyond the periphery of the drum and terminates in a fork 41, which straddles a cross-head 42 secured on the end of a piston rod 43. The cross-head is supported by a stationary slide or support 44 and the piston rod is secured to a piston mounted on a cylinder 45. The piston therein is intermittently reciprocated by water or fluid under pressure, controlled 20 by a four-way valve 46. Two of the ports on the valve 46 are connected by means of pipes 47 with a source of water supply under pressure. The other two ports on the valve 46 are connected with opposite ends of 25 the cylinder 45 through means of pipes 48.

30 A cam 49 is secured on the shaft 19. This cam intermittently engages a rocker arm 50. This arm is connected through means of a link 51 with a crank arm extension 52 on the valve 46. The turning movement of the cam 49 intermittently changes the position of the valve 46; that is, water under pressure is alternately admitted to opposite ends of the cylinder 47 and an intermittent 35 reciprocal movement is thus transmitted to the piston rod and the cross-head 42, this movement being again transmitted to oscillate the arm 40, which is freely journalled on the tubular shaft B which carries the 40 drum. A pawl 52^a is carried by the arm 40 and this engages the notches 38 in the flange of the drum. The arm 40 moves freely in the direction of arrow *a*, and the drum remains stationary during this period, 45 but pawl 52^a engages the notches 38 during reverse movement of the arm 40 and thus transmits an intermittent step by step rotary movement to the drum, pawl 52^a being automatically released with relation to the 50 notches 38 when the full line position shown in Fig. 2 is reached, as a pin on the pawl engages an extension 53 of the link 51; that is, the pin on the pawl rides up on the extension and thus lifts the pawl with relation to the notches 38, and arm 40 is therefore free to move in the direction of arrow *a* without transmitting any movement to the drum. The movement of the piston within the cylinder 45 would be constant 55 from end to end unless means were employed

for slowing down the movement of the piston when it reaches the end of its stroke. Such means are provided and will herein-after be described.

It might be stated that it is more or less 70 essential to slow down the movement of the piston when it approaches the end of the stroke, as it is desirable to bring the drum to a gradual or slow stop.

By again referring to Fig. 4, it will be 75 noted that the forward end of the cross-head 42 is provided with a cam 54. This cam is employed for the purpose of slowing down the motion of the piston within the cylinder 45 and consequently the step by step movement of the drum when a stop position is being reached; that is, movement of the cross-head in the direction of the arrow *b* also imparts movement to the link 51. As the cross-head reaches the end of its stroke, 80 cam 54 engages a pin 55 on link 51 and thus gradually turns the valve 52 to closed position. This movement is independent of cam 49 and it slows down the motion of the piston and the movement of the drum so that the drum will come to a slow and gradual stop. The cam 49 then comes into 85 action and the position of the valve 46 is reversed. Water under pressure is thus admitted to the opposite end of the cylinder, 90 and the piston, together with the cross-head and arm 40, is returned in the direction of arrow *a*.

95 A detail description of the secondary molds and the valve mechanism actuating the same will now be described, and particular reference will be made to Figs. 5, 7, 8 and 14. The molds E are identical in construction and they are supported in pairs 100 on bracket arms D, these bracket arms being bolted to the outer surface of the drum, and as they extend from end to end of the drum, it is possible to arrange a number of pairs of molds, such as shown at E, in line formation, this being particularly 105 shown in Fig. 2. The description of one pair of molds is, however, sufficient and such 110 description will now be given.

115 By referring to Figs. 8 and 14, it will be noted that the secondary molds consist of plates, the center portion of which is raised, as indicated at 60. Formed in the direct center of the plate are four ports, as shown at 61, and formed in the surface of the plate and radiating from the ports 61 are a suitable number of channels or grooves 62. The bracket D is hollow and so are the secondary mold plates 60. The ports 61 communicate with the hollow spaces and also with the radial grooves 62. The hollow spaces are intermittently subjected to a suction and a pressure action and this action is depended upon to dry the pulp articles and to finally discharge them. The hollow spaces must, 120 therefore, be connected with a suction or 125

vacuum pump and also with an air compressor or other source of air supply, and automatically actuated valves must be employed for the purpose of controlling the flow of the fluid from the pumps. This is accomplished as follows:

By referring to Fig. 7, it will be noted that the main hollow shaft B is divided into two sections by means of an inner partition 65. The end of the shaft shown at 66 on one side of the partition is connected with a suction pump (not here shown) by means of a pipe 67. The other end of the shaft or pipe disposed on the opposite side of the partition 65 is connected with a source of air under pressure through means of a pipe 68. The tubular shaft is provided with two sets of ports such as indicated at 69 and 70, and these ports are intermittently brought into communication with pipes 71, which extend radially from a housing generally indicated at 72, the inner ends of the pipes 71 being in communication with the housing 72, and the outer ends of the pipes 71 being in communication with the hollow brackets D, which support the secondary molds E. A pair of cooperating valves 74 and 75 is employed in connection with each pipe 71. The housing 72 is divided into two compartments 76 and 77 by means of a central partition. Compartment 76 is always subjected to air under pressure, while the compartment 77 is maintained under a desired vacuum. When valves 75 are opened, a suction is created in pipes 71 and the molds connected therewith, and when valves 74 are opened, air under pressure is delivered to pipes 71 and the molds connected therewith. Means are employed for automatically opening and closing the valves 74 and 75 at predetermined intervals, during the step by step rotation of the drum, and this is accomplished as follows:

By referring to Figs. 5 and 7, it will be noted that valve 75 is provided with a tubular stem and that the stem of the valve 74 projects through this tubular stem; further, that both valves are normally maintained in a closed position by means of an intermediate spring. It will also be noted that valves 74 and 75 are mounted in central alignment with relation to each other, and that they are actuated by a common rocker arm or lever 78 pivotally supported in a bracket disposed below the valve stems. One end of the lever is adapted to actuate the valve stems. It either engages the lower end of the tubular valve stem or a collar or head 79 secured on the lower end of the central valve stem which actuates valve 74. The opposite end of the lever is provided with a roller which extends into a channel-iron track generally indicated at 80. This track extends from the point indicated at 81 to the point indicated at 82, and it imparts a

rocking movement to the lever so that the inner end engages the tubular valve stem and retains the valve 75 in an open position. In other words valve 75 remains open from the point 81 to the point indicated at 82 or during the major portion of the revolution of the drum. The channel track is offset between the points 81 and 82, and means are employed for transferring the rocker arms from the main channel track section 80 to the offset portion indicated at 83, the means employed being a pair of slides indicated at 84 and 85. These slides are actuated by rocker arms 86 and the rocker arms are in turn actuated by a pair of cams 87 secured on the cam shaft 19. These cams have two elevations, such as indicated at 88 and 89, the elevations engaging rocker arms 90, which are connected with the rocker arms 86 through means of a pair of links or rods 91. Just as the drum is reaching a stop position, the slides 84 and 85 assume a position in alignment with the ends of the main channel track 80 and the ends of the rocker arms thus enter the respective slides and the drum comes to a complete stop when the rocker arms have entered. At this moment the high points 88 of the cams engage the rocker arms 90 and impart movement thereto. This movement is transmitted through the links 91 to the rocker arms 86 and is in turn transmitted to the slides, forcing them inwardly. This inward movement of the slides imparts a rocking motion to the rocker arms and the inner ends of the arms engage the heads or collars 79 of the valves 74. They are thus opened and air under pressure enters the pipes 71 and the molds connected therewith. An air blast will thus pass through the molds and the completed containers will be discharged into the discharge chute I and will be carried away by the conveyor belt L, and an air blast will also pass through the secondary molds which are in alignment with the primary molds H. The molds H are at that time undergoing a pressure or squeezing action and the air blast passing through the primary molds thus assists in removing excess water. The high points of the cams 87 are very small and valves 74 are thus only momentarily opened to permit a quick air blast to take place. It might also be stated that the cams 87 are slightly advanced with relation to each other, so that one valve 74 after the other is opened. Two air blasts therefore take place in successive order and air is in this manner conserved. The cam continues rotating and the high points thus move away from the rocker arms 90 and the intermediate sections 89 of the cams then engage the rocker arms. This causes the valves 74 to close, as the slides will then move into align-

ment with the ends of the offset portion 83 of the channel track. Movement is at this time imparted to the drum and one lever moves into the offset portion of the channel 5 track, while the other lever moves out of its slide 85 and into the main portion of the channel track indicated at 81. The main channel imparts a movement to the rocker arm, which opens valve 75, and the mold 10 is thus subjected to a suction action and it remains under suction action during the major portion of the rotation of the drum or until the point 82 is reached, when it is again subjected to an air blast to discharge 15 the completed pulp article. The rocker arm which travels in the offset portion of the channel track retains both valves in closed position, so that the molds are neither subjected to suction nor blast action 20 while travelling from discharge position to a position where pulp is again applied. From then on the pulp is subjected to a suction action and as the housing surrounding the drum is supplied with warm air, 25 it is obvious that this air will be drawn through the pulp and that it will become rapidly dry, the pulp article being completely dry when the point 82 is reached, when it is discharged, as previously stated, 30 by an air blast.

The general operation of the machine will be as follows: Pulp of a predetermined consistency is continuously circulated through the tank F. The primary molds H 35 are intermittently submerged and raised, and when assuming the submerged position their inner surfaces are coated with pulp, the thickness of pulp applied to the inner surfaces being determined by the consistency of the pulp in the tank and the time period which the molds are permitted to remain submerged and vacuum carried. The primary molds are then raised by means 40 of the pistons and the arms 6 to the vertical full line position shown in Fig. 1, where the pulp is subjected to three simultaneous actions, to-wit, a suction action, caused by opening of the valve 18, a blowing action, due to the opening of one of the valves 74, 45 and a pressing action, due to the pressure exerted between the molds when assuming the position shown in Fig. 1. The blowing action, the pressing action, and the suction action are an important feature of the present invention as they remove all excess water and in fact the major portion of the moisture content of the pulp article, and a comparatively small amount of moisture is thus left to be removed during the drying operation. It should also be noted that the arms 6 assume a vertical position during this period and that the water expressed or removed is thus free to drain downwardly through the hollow arms and to escape through the tubular shafts 3 and 4.

It should also be noted that the primary mold plates 9 (see Figs. 8 and 14) are grooved around the edges, as indicated at 9^a. This is also important as it permits a free drainage and removal of the water from the upper portion of the pulp article. It should also be noted that no positive movement is imparted to the primary molds as they are actuated by means of the pistons or vanes 5; that is, upward movement of 75 the primary molds is merely limited by the thickness of pulp interposed between the primary and secondary molds, and it is therefore possible to apply a greater or smaller thickness of pulp without interfering with the free operation of the molds when assembled. In other words, the movement of the primary molds is more or less flexible as the pistons 5 are merely actuated by a suitable liquid or fluid under pressure, and the pistons 5 will, therefore, move outwardly until the movement of the arms 6 and the molds carried thereby is stopped or resisted. Also, any pressure may be obtained during the squeezing action by merely increasing or decreasing the pressure of the motive fluid or liquid employed. There is a fourth action which takes place during the assembling of the molds, to-wit, 80 that of reinforcing the edges or rim of the pulp article, as indicated at 9^a, this reinforcement being obtained when the primary mold moves into engagement with the secondary mold; that is, the secondary mold or the edge shown at 35 serves as a scraper and as such scrapes the pulp indicated at 9^c (see Fig. 15) to a compact or thickened mass, as indicated at 9^a.

After the water and excess moisture have been expressed by means of the squeezing, blowing, and suction action, and after the formation of the reinforced flange has taken place, the pulp article is transferred, as previously described, to the secondary molds, and the primary molds are returned to submerged position, so that they may again be recoated with pulp.

During the separation of the primary and secondary molds, and during the submersion of the primary molds, drum C is advanced one step to bring a new set of secondary molds into position.

The secondary molds to which the pulp has previously been transferred will thus be advanced to the position shown at 90. (See Fig. 1.) The molds are now subjected to the action of the warm air, which is circulated through the housing, and as the suction valve 75 remains open during the major portion of the rotation of the drum, it can be seen that warm air is drawn through the secondary molds and the pulp container carried thereby, and the pulp container is thus rapidly and thoroughly dried before the discharge position is reached. An air blast is

here applied and the pulp containers are therefore merely blown off into the discharge chute I, where they fall by gravity onto the conveyor belt L, which removes them from the machine.

The main functions which the secondary molds perform are, first, that of receiving the pulp containers which have been formed by the primary molds H; secondly, that of 10 cooperating with the primary molds to form the reinforcing edges on the pulp containers; third, that of maintaining the pulp containers in proper shape while drying; fourth, that of drying the pulp containers; and fifth, 15 that of discharging the same.

The method of drying the pulp containers is another important feature of the present invention; that is, a constant temperature is maintained in the secondary molds 20 as warm air is circulating through and around them during the major portion of the revolution of the drum. The molds are not submerged to receive the pulp and as such are not intermittently subjected to 25 intermittent cooling and heating action. It is due to the fact that a substantially constant temperature is maintained that efficient and rapid drying of the containers is insured.

To obtain proper registration of the primary and secondary molds when squeezing the pulp and transferring it to the secondary molds, a plurality of large dowel pins are employed, as indicated at 92. The dowel pins are carried by the primary molds and 35 recesses for their reception are formed in the secondary molds. These pins are also of considerable importance as they certainly insure proper register of the molds when assembled.

40 The machine is otherwise automatic in operation as the entire mechanism is driven by fluid or liquid actuated motors, the fluid either entering under pressure or passing through the mechanism under a partial vacuum. The fluid flow is in turn controlled by a valve mechanism which is actuated by the single cam shaft 19, and perfect timing and cooperation of all parts are thus insured. Practically all parts of the mechanism are 45 intermittent in operation, but the cam shaft 19 is continuously driven and the cams are so positioned that the valves are actuated at proper time intervals.

The machine, as constructed, is decidedly 55 adapted to quantity production as the drum C may be made as long or as large in diameter as desired, and similarly the brackets D. In other words the brackets D may contain 60 three sets of secondary molds as shown in Fig. 2, or as many additional sets as desired. With three sets of secondary molds, as shown in Fig. 2, it is obvious that six pulp containers will be formed and transferred to the molds in unison and that six completed 65 containers will be discharged into the chute

I whenever a bracket D moves into position with relation thereto.

In the description so far rendered reference has only been made to one pair of primary molds, but it is obvious that there will be 70 three pairs, if three pairs of secondary molds are carried by the drum. Only one set of valves 74 and 75 has been described, but it is understood that there is one set of such valves for each pipe 71, several sets of valves 75 being shown in Fig. 5.

While certain features of the present invention are more or less specifically illustrated, I wish it understood that various changes in form and proportion may be resorted to 80 within the scope of the appended claims. I similarly wish it understood that the materials and finish of the several parts employed may be such as the experience and judgment of the manufacturer may dictate or various 85 uses may demand.

Having thus described my invention, what I claim and desire to secure by Letters Patent is—

1. In a machine of the character described, 90 a pulp containing tank, a primary mold adapted to be intermittently submerged and elevated with relation to the pulp in the tank, a drum disposed above the tank, a plurality of interspaced secondary molds 95 carried by the drum, means for imparting a step by step intermittent rotary movement to the drum to bring the secondary molds one by one into register with the primary mold, means for applying a coating of pulp to the primary mold when submerged in the pulp tank, means for elevating the primary mold to a position in engagement with a secondary mold, means for transferring the pulp from the primary 100 to said secondary mold, means for drying the pulp on the secondary mold, and means for removing the pulp when dry. 105

2. In a machine of the character described, 110 a pulp containing tank, a primary mold adapted to be intermittently submerged and elevated with relation to the pulp in the tank, a drum disposed above the tank, a plurality of interspaced secondary molds 115 carried by the drum, means for imparting a step by step intermittent rotary movement to the drum to bring the secondary molds one by one into register with the primary mold, means for applying a coating of pulp to the primary mold when submerged in the pulp tank, means for elevating the primary mold to a position in engagement with a secondary mold, means for transferring the pulp from the primary 120 to said secondary mold, means for drying the pulp on the secondary mold, and means for automatically removing the pulp when dry. 125

3. In a machine of the character described, 130 a pulp containing tank, a primary mold

adapted to be intermittently submerged and elevated with relation to the pulp in the tank, a drum disposed above the tank, a plurality of interspaced secondary molds carried by the drum, means for imparting a step by step intermittent rotary movement to the drum to bring the secondary molds one by one into register with the primary mold, means for applying a coating of pulp to the primary mold when submerged in the pulp tank, means for elevating the primary mold to a position in engagement with a secondary mold, means for transferring the pulp from the primary to said secondary mold, means for drying the pulp on the secondary mold, and means for supplying air under pressure to the secondary mold to remove the pulp when dry.

4. In a machine of the character described, a pulp containing tank, a primary mold adapted to be intermittently submerged and elevated with relation to the pulp in the tank, a drum disposed above the tank, a plurality of interspaced secondary molds carried by the drum, means for imparting a step by step intermittent rotary movement to the drum to bring the secondary molds one by one into register with the primary mold, means for supplying a coating of pulp to the primary mold when submerged in the pulp tank, means for elevating the primary mold to a position in engagement with a secondary mold, means for transferring the pulp from the primary to said secondary mold, means for surrounding the secondary mold and pulp with warm dry air, means for maintaining a suction within the secondary mold so that the air will pass through the pulp and the mold to dry the pulp, and means for discharging the pulp when dry by passing air under pressure in a reverse direction through the mold.

5. In a machine of the character described, a pulp containing tank, a primary mold adapted to be intermittently submerged and elevated with relation to the pulp in the tank, a drum disposed above the tank, a plurality of interspaced secondary molds carried by the drum, means for imparting a step by step intermittent rotary movement to the drum to bring the secondary molds one by one into register with the primary mold, means for applying a coating of pulp to the primary mold when submerged in the pulp tank, means for elevating the primary mold to a position in engagement with a secondary mold, means for subjecting the pulp to a squeezing action, an air blast and a suction action when the molds are brought into engagement to remove excess water and moisture, means for transferring the pulp from the primary to said secondary mold when the water and excess moisture have been removed, means

for drying the pulp on the secondary mold, and means for removing the pulp when dry.

6. In a machine of the character described, a pulp containing tank, a primary mold adapted to be intermittently submerged and elevated with relation to the pulp in the tank, a drum disposed above the tank, a plurality of interspaced secondary molds carried by the drum, means for imparting a step by step intermittent rotary movement to the drum to bring the secondary molds one by one into register with the primary mold, means for applying a coating of pulp to the primary mold when submerged in the pulp tank, means for elevating the primary mold to a position in engagement with a secondary mold, means for subjecting the pulp to a squeezing action when the molds are brought into engagement, means for simultaneously passing a current of air through the molds and the interposed pulp to remove excess water and moisture, means for reversing the flow of air through the molds and pulp to transfer the pulp from the primary mold to the secondary mold, means for drying the pulp on the secondary mold, and means for removing the pulp when dry.

7. In a machine of the character described, a pulp containing tank, a fluid actuated motor, a primary mold adapted to be intermittently submerged and elevated with relation to the pulp in the tank through means of the fluid actuated motor, a drum disposed above the tank, a plurality of interspaced segmental molds carried by the drum, a fluid actuated motor for imparting a step by step intermittent rotary movement to the drum to bring the secondary molds one by one into register with the primary mold, means for applying a coating of pulp to the primary mold when submerged by suction action, means for delivering fluid to the first named motor to elevate the primary mold to a position in engagement with a secondary mold, said means also subjecting the pulp to a squeezing action, means for applying an air blast and a suction action during the squeezing action to remove the water expressed and excess moisture, means for transferring the pulp from the primary to the secondary mold by an air blast and a suction action, means for drying the pulp on the secondary mold by passing a current of warm air through the pulp and the mold, means for removing the pulp when dry by passing a reverse air blast through the mold, valves controlling the flow of fluid to the drum actuating motor, valves controlling the flow of fluid through the respective molds, and a single controlling member for intermittently opening and closing said valves at predetermined time intervals.

8. In a machine of the character described,

- a pulp containing tank, a fluid actuated motor, a primary mold adapted to be intermittently submerged and elevated with relation to the pulp in the tank through means of
- 5 the fluid actuated motor, a drum disposed above the tank, a plurality of interspaced segmental molds carried by the drum, a fluid actuated motor for imparting a step by step intermittent rotary movement to the drum
- 10 to bring the secondary molds one by one into register with the primary mold, means for applying a coating of pulp to the primary mold when submerged by suction action, means for delivering fluid to the first named
- 15 motor to elevate the primary mold to a position in engagement with a secondary mold, said means also subjecting the pulp to a squeezing action, means for applying an air blast and a suction action during the squeezing
- 20 action to remove the water expressed and excess moisture, means for transferring the pulp from the primary to the secondary mold by an air blast and a suction action, means for drying the pulp on the secondary
- 25 mold by passing a current of warm air through the pulp and the mold, means for removing the pulp when dry by passing a reverse air blast through the mold, valves controlling the flow of fluid to the primary
- 30 mold actuating motor, valves controlling the flow of fluid to the drum actuating motor, valves controlling the flow of fluid through the respective molds, a continuously rotating shaft, and a plurality
- 35 of cams mounted thereon whereby all of the valves are actuated at predetermined time intervals.
9. In a machine of the character described, a pulp receiving mold adapted to be intermittently submerged and elevated with relation to a pulp containing tank, a pulp drying mold elevated with relation to the tank and movable with relation thereto, means for transferring pulp from the receiving to the drying mold, and means for maintaining the drying mold at a substantially predetermined drying temperature.
10. In a machine of the character described, a pulp receiving mold adapted to be intermittently submerged and elevated with relation to a pulp containing tank, a pulp drying mold elevated with relation to the tank and movable with relation thereto, means for transferring pulp from the receiving to the drying mold, and means for maintaining the drying mold at a substantially predetermined drying temperature by maintaining a flow of warm dry air through the pulp and the mold.
11. In a machine of the character described, a pulp receiving mold adapted to be intermittently submerged and elevated with relation to a pulp containing tank, a pulp drying mold elevated with relation to the tank and movable with relation thereto, means for transferring pulp from the receiving to the drying mold, means for maintaining the drying mold at a substantially predetermined drying temperature by maintaining a flow of warm dry air through the pulp and the mold, and means for momentarily passing a reverse air blast through the mold to blow off the pulp when dry. 70

GEORGE H. KIRSCH.
